UNITED STATES PATENT OFFICE.

ALBERT FENIMORE ROCKWELL, OF BRISTOL, CONNECTICUT.

DESIGN FOR A BICYCLE-BELL.

SPECIFICATION forming part of Design No. 27,146, dated June 1, 1897.

Application filed December 26, 1896. Serial No. 617,107. Term of patent 7 years.

To all whom it may concern:

Be it known that I, ALBERT FENIMORE ROCKWELL, of Bristol, Hartford county, Connecticut, have invented and produced a new and original Design for the Gongs of Bells, 5 of which the following is a specification, reference being had to the accompanying drawings, forming a part thereof.

Of the drawings, Figure 1 is a plan view of 10 my gong. Fig. 2 is a perspective view looked at from the side. Fig. 3 is a view in part perspective and in part sectional.

The design relates to the general configuration of the gong of a bell, substantially 15 as hereinafter described, but particularly to a bell provided with the particular form of bead which is around the edge of the gong.

A is the gong. About its edge is formed what I call a "square bead," having the faces B and C at right angles to each other, all so 20 constructed as to form a gong of an exceedingly attractive form.

I claim as my invention—

The design for a gong, substantially as 25 herein shown and described.

In testimony whereof I have signed this specification in the presence of two subscribing witnesses.

ALBERT FENIMORE ROCKWELL.

Witnesses:

GEORGE A. BURNELL,
JOHN J. JENNINGS.
